UNITED STATES PATENT OFFICE

WALTHER KOHNIGER, OF BERLIN-WILMERSDORF, GERMANY

ICE SKATING RINK

Application filed November 21, 1929, Serial No. 497,237, and in Germany April 25, 1929.

Artificial ice rinks are known in which the system of cooling tubes for freezing the water on the rink are disposed in a granular or similarly constructed mass.

5 The invention contemplates an improvement in such ice rinks and is formed as follows: A suitably strong bed is constructed from a material which is highly permeable to water, porous and at the same time is a good heat insulator. The cooling system is disposed upon or near to the upper side of this bed and finally a surface layer is laid thereon composed also of granular material whose porosity and permeability to water is 10 however essentially smaller than the material used for the preparation of the bed.

The upper layer which is referred to as the surface layer can be correspondingly thin. The material used for this purpose must have 15 a certain porosity in order to let water pass through in small quantities or relatively slowly. It should however have such a small porosity that if water is placed on this layer for the purpose of being frozen it is not further 20 passed through the surface layer and there is only a small opposition to the passage of heat. Thereby is obtained a greater effect from the freezing process for a given amount of heating effort. The material for the surface layer may be such that this ice rink surface may be used not only as the basis for an ice rink but also for other purposes such as for sports. By a careful choice in the assembly of the 25 material, the ice rink can after being put out of operation that is, after thawing of the ice and permitting the water present on the surface layer to drain off through the bed, be used, for example, as a tennis court.

30 For this purpose, the bed (under layer) must have the following properties: It should have good permeability for water that is to say, good porosity in order that water which passes through the surface layer can quickly 35 drain away. In addition the bed should be so constructed that it forms a lower heat insulator. Moreover both the selection of a material suitable for the purpose and the great porosity of the material is facilitated because 40 the small air spaces present in this material

in the desired manner increases the degree of insulation of the bed.

As material for the bed according to the invention, slag, for example coal slag or blast furnace slag or equivalent material may be 45 employed.

In order that the tube system, through which the cooling material runs, shall not be subjected to earth movements or unfavorable influences a special disposition of the 50 tube systems is provided according to the invention. The result is thus attained that the ice rink, when not in use as a skating ice surface, can be used for sports, especially as a tennis court but must however be resilient. 55 According to the invention a good elasticity of the ice rink is attained which rink can be used also as a sports place, by laying the tubes of the cooling system on sleepers which are sufficiently resilient. The sleepers can be 60 formed from wood or from iron and can advantageously be laid in a suitable manner on the water-permeable bed.

The invention is represented in the drawings in several embodiments wherein,

Fig. 1 is a section through the improved ice rink,

Fig. 2 a plan view of part of the rink,

Fig. 3 is a section through an ice rink wherein the tube system is supported on 70 sleepers,

Fig. 4 is an additional vertical section of the ice rink illustrated in Fig. 3 and,

Fig. 5 is a plan view of the ice rink according to Fig. 3.

According to Fig. 1 the ice rink comprises a sufficiently solid bed 1. This bed is constructed for example from a 40 to 50 cm. thick layer of slag, for example, coal slag particularly blast furnace slag. These materials 80 have a very great porosity so that water can drain through quickly from the upper side of the layer.

The cooling system is arranged on the upper side of the bed 1. The cooling system 85 comprises cooling coils 2 which are arranged in a known manner. On the bed on top of the cooling system 2, the surface layer 3 is provided. This, as has been stated should be permeable to water, though to a much less 90

degree than is the bed 1, and it should have better heat conducting properties than does such bed. It may comprise a granular material such as is commonly used in the production of tennis courts or sports areas. Thus, 5 for example, where the rink is to be adapted for use as a tennis court when not used as an ice rink the surface layer 3 may be formed of any of the materials which are commonly used at the present time for forming hard 10 tennis courts, amongst which there may be mentioned fine sand, more or less fine brick dust, fine red colored slag or in some cases fine grained clay or earth or mixtures of these. Where it is desired that the rink 15 should be suitable for sports purposes such as for sprinting or jumping when not in use as an ice rink this upper surface layer may be formed of other materials which are employed at the present time for the production 20 of surfaces for these purposes. This material has in accordance with the invention a smaller porosity than the material of the bed 1 in order that, when the ice rink is to be brought into operation, water placed on 25 the surface does not permeate this layer too quickly. On the other hand, the material must have a definite, if small, porosity for the above given thermo-technical reasons and 30 in order to assure a flowing off and draining of the surface layer in a comparatively small time so that the rink can be put out of operation by stopping the refrigerator machine and the surface employed as a sports area, 35 within a relatively short time thereafter. The layer 3 can, as will be seen from the drawings, be essentially thinner (for example, 3 cm. clear above the tubes) than the bed 1.

The characteristic of the invention lies in 40 the provision of two layers for the ice rink of which the lower one is of high water-permeability and porosity and good heat insulating capacity while the other upper layer is essentially of smaller porosity, of good heat 45 conductivity and can be employed as a sports surface. The cooling tube system is arranged within one or other of these two layers or partly in one layer, and partly in the other.

50 As the invention also contemplates the use of the upper surface for sports purposes particularly as a tennis court it is desirable that the upper layer should have a suitably good resiliency. In order to attain this and to prevent displacement of the tube or pipe system the latter is, according to the invention laid upon sleepers in the same way as railway rails are laid upon sleepers. The sleepers should be according to the invention suitably 55 resilient, as by being made from wood, or they may be made from metal for example iron. This further modification of the invention is illustrated in Figs. 3 to 5. Here 1 is the bed which is prepared in the same manner as has been described with reference to

Fig. 1. On this bed are laid the sleepers 4 on which the tube system 2 is disposed, and finally, the surface layer 3 is laid, whose properties have already been described with reference to Fig. 1. In this view wooden 70 sleepers 4 are indicated.

In Fig. 4 the disposition of the sleepers and the tube system is shown by way of example, and here iron sleepers 4' are represented. In Figs. 4 and 5 the connection of the tube 75 system to the refrigerator instrument is illustrated. 5 represents the entrance pipe for the cooling material for example cooled brine and 6 is the return pipe for this cooling material, 7 and 8 are controlling valves. The pipes 5 and 6 are connected in any desired way with suitable refrigerating apparatus. 80

From the foregoing description and the drawings it will be understood that these 85 embodiments are merely given by way of example of the invention and are further merely given as schematic diagrams.

The invention above described as characterized in the subsequent claims can naturally be altered in different ways and constructed somewhat differently. 90

I claim:

1. In an artificial ice rink, the combination of a water-permeable porous and heat 95 insulating material formed into a bed, a cooling pipe system laid on such bed and a surface layer disposed above the cooling pipes which is formed from a granular material whose porosity, water-permeability and heat insulating capacity is essentially less than that of the bed but through which water may slowly pass to drain the upper surface. 100

2. In an artificial ice rink, the combination of a bed formed of slag, a cooling tube system disposed thereon and a surface layer which has less porosity, water-permeability and heat insulating capacity than that of the bed but through which water may slowly 105 pass to drain the upper surface. 110

3. In an artificial ice rink, the combination of a bed formed of blast furnace slag with a superposed cooling tube system and a surface layer which is of less porosity, 115 water-permeability and heat insulating capacity than that of the bed but through which water may slowly pass to drain the upper surface.

4. In an artificial ice rink, the combination of a bed formed of water-permeable, porous and heat insulating material, a superposed cooling tube system and a surface layer which is formed of a granular material whose porosity, water-permeability and heat insulating capacity is essentially less than that of the bed and is also thinner than the said bed but through which water may slowly pass to drain the upper surface. 125

5. In an artificial ice rink, the combination 130

- of a bed formed of water-permeable, porous and heat insulating material, a tube system disposed on sleepers on said bed and a surface layer arranged thereon which is formed from a granular material whose porosity, water-permeability and heat insulating capacity is essentially less than that of the bed but through which water may slowly pass to drain the upper surface.
6. In an artificial ice rink, the combination of a bed formed of highly water-permeable, porous and heat insulating material, a tube system disposed upon resilient sleepers on said bed and a surface layer disposed thereon formed from granular material whose porosity, water-permeability and heat insulating capacity is essentially less than that of the bed but through which water may slowly pass to drain the upper surface.
- 10 7. In an artificial ice rink, the combination of a bed formed of a highly water-permeable, porous and heat insulating material, a tube system disposed on resilient iron sleepers on said bed and a surface layer disposed thereon which is formed from granular material whose porosity, water-permeability and heat insulating capacity is essentially less than that of the bed but through which water may slowly pass to drain the upper surface.
- 15 8. In an artificial ice rink, the combination of a bed formed of highly water-permeable, porous and heat insulating material, a tube system disposed on wood sleepers on said bed and a surface layer disposed thereon which is formed from granular material whose porosity, water-permeability and heat insulating capacity is essentially less than that of the bed but through which water may slowly pass to drain the upper surface.
- 20 9. In an artificial ice rink a bed composed of a lower permeable layer, a less permeable surface layer through which water may slowly pass and means for freezing water which may be spread over the surface layer, such means being located in the bed in a position approximating the zone where the two layers meet.
- 25 10. In an artificial ice rink, a bed formed of a lower layer of permeable material permitting the drainage of water, a less permeable surface layer and a system of cooling coils located within the bed at the zone approximating that where the two beds meet, the permeability of the surface layer being such as to permit water to remain thereon for a sufficient time to congeal to a solid ice surface when the cooling coils are in operation and to drain away through such layer when the cooling coils are out of operation.

60 WALTHER KOENIGER.
